UNITED STATES PATENT OFFICE.

PETER J. A. SCHNOOR, OF HOLSTEIN, IOWA.

MAIL-BAG-DELIVERY DEVICE.

No. 842,023.

Specification of Letters Patent.

Patented Jan. 22, 1907.

Application filed November 21, 1906. Serial No. 344,386.

To all whom it may concern:

Be it known that I, PETER J. A. SCHNOOR, a citizen of the United States, and a resident of Holstein, in the county of Ida and State of Iowa, have invented an Improved Mail-Bag-Delivery Device, of which the following is a specification.

This invention relates to mail-bag-delivery devices for railway-cars; and it consists, substantially, in the construction, organization, and combination of parts hereinafter described, and illustrated in the accompanying drawings.

One object had in view is to provide devices of this character which shall be simple in construction and effective and reliable in operation.

A further object is to overcome numerous disadvantages and objections common to devices of the kind as hitherto devised.

In the drawings, Figure 1 is a transverse vertical sectional view of a portion of a railway mail-car and showing my improvement embodied in connection therewith. Fig. 2 is a top plan view of my improvement and showing a sectional portion of the car. Fig. 3 is a detail view of the track-derrick or mail-bag support viewed as indicated by the arrow in Fig. 1—that is, looking at the free end of the derrick-arm when it is adjusted to position adapted for holding a mail-bag ready to be taken up by operation of catching devices or crane carried by a mail-car. Fig. 4 is an external view of a mail-car door and adjacent portion of the car side. In the view the bag-catching device or crane is shown arranged in place on the car. Fig. 5 is a detail plan view of the crane-head and a portion of its supporting-arm.

Before proceeding with a more detailed description it may be stated that in the form of my improvements herein shown I employ a specially-constructed derrick at each of the railway-stations or other places at which the mail-bags are to be delivered and taken up by the devices on the car. On the car I employ a specially-constructed oscillatory catching device or crane adapted to be adjusted into position for taking up a mail-bag supported in position on the derrick adapted to be taken up and delivered into the moving car, the catching device or crane being also adapted for depositing a mail-bag from a moving car, leaving it supported on the track-derrick ready to be removed therefrom.

In operation a mail-bag is suspended from one of two supports on the derrick at the station or railway side, and a bag is also suspended from the head at the free or outer extremity of crane, the latter obviously being adjusted outwardly from the side of the car. As the car moves along the mail-bag on the derrick will be taken up by the crane, and the mail-bag on the crane will be taken up by the derrick.

In the following detail description of my invention reference is had to the drawings by the designating characters marked thereon.

In carrying out my invention I employ a derrick A, constructed with a post B, supported in upright position near the railway-track, locating same at a station or other desired position of mail delivery or deposit. On the upper end of the post B a horizontally-supported arm C is provided, the same being supported adapted to turn one hundred and eighty degrees—in other words, ninety degrees on its support from adjusted position thereof ready to take up a mail-bag or support a bag ready to be taken up by the crane on a passing car.

D designates an arm located on the post B above position of the arm C. The arm D has pivotal support near one end thereof on trunnions E, fixedly secured to the post B. In constructing the pivoted end of the arm D, I employ two similar castings F, adapted to be bolted together and fashioned at one end adapted for attachment of the arm member D'. The other end of the casting—that is, its extension beyond the pivotal supports E—is weighted adapted to overweight the member D' portion of the arm, as will be understood, upon reference to Figs. 1 and 2. The object of thus constructing and supporting the arm D is chiefly to adapt its mail-bag-supporting end to be swung upwardly when set free by removal of a bag thereon, as indicated by the arrow in Fig. 1. At the outer end of the vertically-swinging arm D, I secure irons G, constructed with oppositely-projecting flanges or jaws H.

The lower arm C is constructed with a member C', having an iron or casting I at its inner end, the iron I being constructed in two similar parts adapted to be bolted together and adapted to clampedly hold the adjacent end of the arm member C' and, further, to surround or have journaled support on the post B, permitting free lateral turning there-

on. The arm C is supported on the post B by a fixed shoulder or two-part iron J, bolted or otherwise secured in position, substantially as shown by Figs. 1 and 3.

5 Upon reference to Fig. 1, it will be noticed that the irons I J are constructed the former with a downwardly-extended projection K and the latter with an upwardly-projecting extension L, (see Fig. 1,) the said extensions 10 K L being arranged on the irons I J, adapted to limit turning action of the arm C to ninety degrees from its mail-bag-supporting position, as will be understood.

On the upper side of the supporting-iron J, 15 I provide a rib or pin M, (see Fig. 1,) and I also provide a similar recess or groove N in the under side of the iron I.

It is designed that when the arm C is adjusted adapted to support a mail-bag ready 20 to be taken up by a passing mail-car the rib M and recess N on the respective irons I J shall be arranged into locking engagement, and thereby retain the arms C D in position for delivering or receiving a mail-bag.

25 On the outer end of the arm C, I provide an iron O, constructed with spaced arms P, extending in one direction therefrom, and pins O', extending in the opposite direction, substantially as shown by Fig. 5.

30 Q Q' designate mail-bag holders adapted for suspending a bag on the derrick and also on a crane S, carried by the car. The crane S is constructed with an arm T, having a mail-bag take-up device U at its outer end.

35 The take-up device U is constructed with two spaced bars W arranged on the outer end of the arm T with their ends extending in opposite directions from support on the arm T. Upon reference to Figs. 2 and 3 it 40 will be noticed that the extreme ends A² of the bars W are bent outwardly. Between the bars W, I arrange rollers A³ and locate them adjacent to attachment of the arm T.

A⁴ A⁵ denote dogs or bolts consisting of 45 two members in each thereof and with the members entered transversely through the bars W. The dogs or bolts are yieldingly held forced into abutting position of their inner ends by means of springs A⁶, the springs 50 being secured to the outer side of the bars W at a point between their ends, as shown by Figs. 2 and 4.

It will be noticed that the abutting ends of the dogs A⁴ are made rounding on both 55 sides, while the same ends of the dogs A⁵ are rounded on one side, leaving their opposite side in alinement.

Yielding dogs and rollers as above described are provided on opposite ends of the 60 bars W, substantially as shown by Fig. 4.

The crane-arm T has support on a bar D², the latter being held by brackets E², located at opposite sides of the car-door, substantially as shown by Figs. 2 and 4. The inner end of 65 the crane-arm has a handle F², whereby to

swing outwardly the mail-bag or take-up and delivery end thereof, and on said handle I provide a hand-grip G² of common form. The hand-grip is designed for adjustment of a dog or bolt H² out of engagement with a circular rack or perforated plate I² through means of a connecting-rod J². It will be understood that the bolt is yieldingly held in locking position, and it will be further understood that the crane-arm may be adjusted 75 adapted to deliver and take up mail-bags or be turned down and secured as adjusted by the means above described.

Referring again to Fig. 5 of my drawings, it will be noticed that I provide thereon two 80 dogs P², the same being constructed and arranged in all respects similar to the like parts A⁵ in Figs. 2 and 4. A roller P⁴, similar to the rollers A³ shown by Figs. 2 and 4, is arranged between the bars P, Fig. 5, and the 85 extreme ends of said bars P are bent outwardly and upwardly similar to the ends A² of the bars W.

The bag-hangers Q are constructed of a suitable rope having enlarged heads Q² and 90 their lower ends adapted to be looped around the bag and the loop end of the rope being provided with any suitable fastening device (indicated at Q³, Fig. 1) whereby to secure it around the bag.

95 The operation is as follows: The clasp end of the rope Q is coiled around a mail-bag and secured as shown and described and the bag arranged suspending on the track-derrick by inserting the rope-head Q² between the flanges or jaws H on the derrick-arm D. The lower portion of the bag-attaching rope Q is placed between the pins or projections O' O', thereby to hold the bag against swinging action. It will be understood that when suspending a bag on the track-derrick to be 100 taken up by a passing mail-car the bag should be arranged on the far side of the derrick from direction in which the mail-car is traveling, as shown by Fig. 5. If a mail-bag 105 is to be delivered from the mail-car, a rope Q' with attaching means similar to the rope Q, is fastened on the bag and the latter arranged suspending from the rearward arms W of the take-up device U at the outer end of the 110 crane-arm T. In arranging the suspending-rope Q' on the rearward bars or arms W rearward in respect to motion of the mail-car it is forced between the abutting-dogs A⁴ and left hanging by its head Q², resting upon the adjacent arms W of the take-up device U. It 115 will be understood that the rope Q' should be left suspended on the bars or arms W, as stated, but positioned thereon between location of the yielding dogs A⁴ and A⁵. Now as 120 a mail-car provided with my take-up device passes a derrick at the track side, the crane-arm being adjusted to position for the take-up device U to be passed between the arms C D on the derrick, it is apparent the forward 125 130

arms W (see Figs. 3 and 4) will engage the rope Q and the latter, through forward impact movement, be forced between the dogs A⁴ A⁵ to position against the roller A³. Obviously continued motion of the car will pull the rope-head Q² from between the jaws H on the derrick-arms D, whereupon the latter will by gravity find supporting-seat upon the said forward arms W and be retained in the seated position stated through confining action of the rear side of the dogs A⁵. During operation or movement of parts just described the bag suspended from the rear arms W of the device U will carry the rope Q' between the arms P at the outer end of the derrick-arm C and force same between their dogs P² to position contacting the stop device or roller P⁴. Now it is apparent that, as both sides of the abutting ends of the dogs A⁴ are rounded, as the crane take-up device is carried along the rope Q' will be pulled, forcing the dogs A⁴ apart, and thus permitting the rope-head Q² to be seated upon the arms P at the outer end of the derrick-arm C.

25 The dogs P² on the bag-supporting arms P being constructed with rear flat sides similar to the like dogs A⁵ on the crane take-up device U, obviously the bag-holding rope Q' will thereby be held, and thereby insuring detachment from the crane take-up arms.

I claim—

1. In mail-bag-delivery devices for cars, a derrick at the station of delivery, comprising a horizontally-adjustable arm, a vertically-adjustable arm, means adapted to hold the arms in bag-supporting position, means effecting vertical adjustment of one arm when it is released, means adapted to hold the vertically-adjustable arm drawn down to bag-holding position, means adapted to secure both the arms at bag-holding position, and means providing support for said arms.

2. The combination in a mail-bag delivery for cars, of a derrick comprising a post, an arm at the upper end of the post, said arm having pivotal support on the post providing it with vertical adjustment, a

counterweight at one end of said vertically-adjustable arm, a lower arm on the post, the lower arm having horizontal adjustment, oppositely-projecting arms at the bag-suspending ends of said adjustable arms, means for attachment to a bag, adapting the bag to be suspended on the derrick-arms, and removed therefrom, and a crane on a car adapted to deliver a bag to supported position on the derrick-arms, and also adapted to take up a bag from supported position on the derrick-arms.

3. The combination with a derrick, comprising horizontally and vertically adjustable bag-supporting arms, and means adapted for suspending the bag, of a crane carried by a car, the crane being adapted for adjustment to deliver and take up bags, a take-up device at the outer end of the crane, the take-up device being constructed with oppositely-projecting bag-engaging arms and dogs on said arms adapted to secure the bags at suspended position.

4. A mail-bag-delivery device, comprising a post, horizontally and vertically adjustable arms on the post, the vertical arm having pivotal support, and counterweighted at one end, a shoulder on the post having a projection on its upper side, the inner end of the horizontally-adjustable arm being provided with a recess adapted to receive said projection on the shoulder, and stop devices whereby to limit movement of the horizontally-adjustable arm.

5. A derrick constructed with upper and lower supporting-arms, jaws on the upper arm, parallel transversely-arranged projecting arms on the lower derrick-arm, dogs and a stop device on the parallel arms, and projecting pins on the lower derrick-arm, said pins being located projecting from one side of the lower derrick-arm.
